[57] CLAIM

The ornamental design for a combined packaging and carrying container for bottles or the like, as shown.

DESCRIPTION

FIG. 1 is a perspective view of a combined packaging and carrying container for bottles or the like showing my new design;

FIG. 2 is a side elevational view;

FIG. 3 is a front elevational view;

FIG. 4 is a top plan view; and

FIG. 5 is an interior perspective view in opened position.

FIG. 3. FIG. 4.
